TELEVISION SYSTEM

Robert E. Shelby, Teaneck, N. J., assignor to
 Radio Corporation of America, a corporation of
 Delaware

Application December 31, 1941, Serial No. 425,015

9 Claims. (Cl. 178—5.6)

This invention relates to an improvement in television systems and more particularly to television transmitters.

It is customary in television transmitting systems to transmit picture and synchronizing signals by means of one modulated carrier and to transmit the related sound signals by means of a second modulated carrier. Two separate carriers, one for sound and the other for picture and synchronizing signals are used. These two carrier frequencies are displaced from each other by a predetermined and fixed frequency separation. According to the present standards of television transmission, an overall band of six megacycles is provided within which picture signals, synchronizing signals and related sound signals must be transmitted. Furthermore, according to the present standards, the picture and synchronizing signal modulated carrier is positioned 1.25 megacycles above the lower limit of the particular television band whereas the sound modulated carrier is positioned 0.25 megacycle below the upper limit of the allotted frequency band. When the two radio frequency carriers are so positioned with respect to the lower and upper limits of the allotted band, the displacement between the two carrier frequencies is then 4.50 megacycles.

In the transmission of high fidelity television picture signals considerable band width is required in view of the relatively high frequencies which are produced at the transmitter as a result of the scanning operation. If high fidelity pictures are to be reproduced at a receiver, picture signals ranging from substantially zero to frequencies of the order of from 4 to 5 megacycles must be transmitted. In order to conserve space in transmission, the present television standards require that a portion of the produced side bands resulting from modulation of the picture signal carrier be suppressed so that substantially only single side band transmission results.

Under the present standards of transmission and with a spacing of 4.50 megacycles between the picture carrier and the sound carrier, naturally picture signals in excess of 4.25 megacycles are not ordinarily transmitted since the selective characteristics of the intermediate frequency portion of the television picture receiver cannot be made to cut off perpendicularly. If the picture signal channel of the television receiver is made wider than about 4.25 megacycles, for example, interference from the sound channel will

frequently become apparent in the received television picture.

Present television transmitting cameras are capable of generating picture signal frequencies considerably in excess of 4.5 megacycles and accordingly it is desirable to transmit these frequencies in order to increase the definition of the picture at the receiver. Such an increase cannot be made where the sound and picture carriers are displaced by 4.50 megacycles unless some special provisions are made. In the transmission of color images it is also frequently desirable to use a wider band for the picture frequencies since in the transmission of color images the scanning rate and/or field repetition rate is frequently increased.

It is, therefore, one purpose of the present invention to provide a system whereby the television picture signal channel or band width may be increased without the received image being affected in any way by the related sound signals.

To accomplish the above purpose the sound carrier is entirely interrupted during the transmission of picture signals and the sound frequency modulated carrier is transmitted only during intervals of picture signal line blanking. The synchronizing signals are transmitted by the same carrier as are the picture signals but the sound signals are transmitted by an entirely separate carrier frequency and, in accordance with this invention, the periods of transmission of sound signals occur only during the transmission of horizontal or line blanking signals by the picture and synchronizing signal carrier.

According to the present United States television standards, the horizontal blanking interval occupies about 16% of a horizontal deflection cycle. During the remaining 84% of the horizontal deflection cycle picture signals are transmitted. During the time that the picture signals are transmitted the sound carrier is entirely eliminated whereas during the time that the horizontal blanking signal is being transmitted the sound carrier is effective to transmit the accompanying sound in the television program.

It is therefore another purpose of the present invention to provide a system wherein the sound carrier is completely interrupted during the transmission of picture signals by the picture signal carrier.

Still another purpose of the present invention resides in the provision of means whereby the sound carrier frequency is effective to transmit sound signals only during the interval when

blanking impulses are transmitted by the synchronizing and picture signal carrier.

A still further purpose of the present invention resides in the provision and the use of a first radio frequency carrier for sound and a second radio frequency carrier for picture and synchronizing signals, with the picture and synchronizing signals transmitted sequentially by the second carrier and with the sound signals transmitted only during transmission of line blanking signals.

A still further purpose of the present invention resides in the provision of means whereby the sound signals are transmitted alternately with respect to picture signals and concurrently with respect to the line blanking signals, the synchronizing signal carrier and the picture signal carrier being identical.

Still other purposes and advantages of the present invention will become more apparent to those skilled in the art from the following detailed specification particularly when considered in connection with the drawing wherein the single figure represents by way of example a preferred form of the present invention.

Referring now to the drawing and particularly to the figure, there is shown a television picture transmitting tube 10 which includes a mosaic or light responsive electrode 12 and an electron gun structure 14. The electron gun structure includes at least a cathode 16, a control electrode 18, a first accelerating anode 20 and a second accelerating anode 22. The second accelerating anode is connected to terminal 24 to which is applied a relatively high positive potential. A potentiometer resistance 26 is connected between the positive terminal 24 and ground or the negative terminal of the source of potential in order that varying potentials may be obtained. The first accelerating anode 20 is connected to a point along the potentiometer 26, the point of connection being adjustable in order to focus the produced cathode ray beam. The cathode 16 is connected to a point on the potentiometer 26 negative with respect to the first accelerating anode whereas the control electrode 18 is connected by means of grid resistance 28 to a point along the potentiometer 26 that is negative with respect to the point where the cathode 16 is connected. This connection is also preferably made adjustable in order that the average beam intensity may be controlled. When proper operating potentials are applied to the electrodes of the electron gun structure a focused cathode ray beam is produced.

In order to control the television transmitting system a master oscillator 30 is provided. This oscillator may be of any desired form and may operate at any appropriate frequency. The master oscillator supplies impulses corresponding to its frequency of operation to the horizontal deflection generator 32 which, in turn, supplies energy to the horizontal deflecting coils 34. The master oscillator 30 also supplies impulses to a frequency divider 36 and the output frequency of the frequency divider corresponds to a predetermined sub-harmonic of the master oscillator frequency. The frequency divider then supplies control impulses to the vertical deflection generator 38. The vertical deflection generator then supplies the desired voltage variations to the vertical deflecting coils 40.

When the deflecting coils 34 and 40 are energized by voltage variations of proper wave form from the horizontal and vertical deflection gen-

erators 32 and 38 respectively, the generated cathode ray beam is caused to scan the light responsive electrode 12 in bilateral directions in order to produce picture signals in the picture signal load circuit including resistance 42. The voltage which is available from the signal plate of the light responsive electrode 12 is then transmitted to a picture signal amplifier 44 by way of coupling condenser 46. The picture signal amplifier may be of any desired form and preferably should have a band width capable of transmitting frequencies from substantially zero to frequencies of the order of at least five megacycles.

In order that the television receivers may be held in synchronous operation with the operation of the television transmitting tube, synchronizing signals must be transmitted for controlling horizontal and vertical deflection generators at the receiver. These synchronizing impulses are transmitted on the same carrier as are the picture signals and are interspersed with the picture signals. The synchronizing signals, according to the present standards, are transmitted in a direction corresponding to black in the picture so that they may be used at the receiver for automatic blanking of the return beam. The master oscillator 30, therefore, supplies impulses to the horizontal blanking and synchronizing signal generator 48 and the horizontal blanking and synchronizing signal generator produces voltage variations of the desired wave form which may be used for picture signal blanking and for synchronizing. Likewise, the frequency divider 36 supplies impulses to the vertical blanking and synchronizing signal generator 50 which, in turn, produces vertical blanking and synchronizing signals of the desired wave form. The energy from the horizontal and vertical blanking and synchronizing signal generators 48 and 50 is then applied to an amplifier or mixer 52 in order that the picture signals may be suppressed or blanked during intervals of synchronization and in order that both the horizontal and vertical blanking and synchronizing signals may be interspersed with the picture signals. At the output of the amplifier and mixer 52, therefore, is derived a series of signals representative of the picture signals and including both the horizontal and vertical blanking pedestal and the horizontal and vertical synchronizing signals. For the purpose of simplicity in so far as this application is concerned, specific details of the blanking pedestal and the so called super-sync impulses are not considered because they do not in any way affect the merits of this invention. Their wave form, naturally, should be such as will conform to the required standards.

The signals which are derived from the amplifier and mixer 52 are then fed to a modulator 54 in order that oscillations derived from a radio frequency oscillator 56 may be amplitude modulated thereby. The amplitude modulated carrier is then applied to a vestigial side band filter 57 and the output from the filter is impressed upon the television transmitting antenna 58 for transmission. If desired, frequency modulation may be employed.

The figure also shows a microphone or sound responsive device 60 which is normally positioned in the television studio and which responds to the sound or aural part of the television program. The audio signals which are available from the microphone or sound responsive device 60 are then applied to an amplifier 62 in order that the amplitude of the audio frequency voltages variations may be increased.

According to the present television standards the picture and synchronizing signal carrier is amplitude modulated by the picture and synchronizing signals whereas the sound frequency carrier is frequency modulated by the sound signals. Accordingly, the output from the amplifier 62 is then supplied to a frequency modulated oscillator 64 in order that the voltage variations produced by the oscillator contained therein may be frequency modulated. In so far as this invention is concerned, it is immaterial what type of frequency modulation is used and a frequency modulating system such as that shown in Crosby application, Serial No. 136,578, filed April 13, 1937, (D-12019) may be used. The frequency modulated oscillations that are derived from the oscillator and frequency modulating device 64 are then applied to an amplifier and/or frequency multiplier 66. This device may be used to increase the amplitude of the signals or to increase the frequency as well as the frequency deviation caused by frequency modulation.

The output from the amplifier and/or frequency multiplier 66 is then supplied by way of condenser 68 to the control electrode of tube 70. This tube includes, in addition to the control electrode, at least a cathode and an anode. The cathode is connected to ground by way of resistance 72 and by-passed condenser 74 while the anode is connected to the source of positive potential by means of anode load resistance 76. In order that the control electrode may be maintained at its proper operating potential with respect to the cathode, a potentiometer 78 is provided, one end of the potentiometer resistance being connected to ground and the other end of the potentiometer resistance being supplied with a negative potential. The control electrode of tube 70 is connected to the movable contact on the potentiometer by means of radio frequency choke coil or inductance 80 and resistance 82.

The potential of the control electrode of tube 70 with respect to its cathode is normally such as will preclude operation of the tube so that the voltage variations from the output of the amplifiers and/or frequency multiplier are not effective to control the tube 70. The control electrode of the tube 70 is also connected to the output from the horizontal blanking and synchronizing signal generator 48 by means of condenser 84. In this connection may be included a wave shaping circuit 85 if such a circuit is necessary. Amplification may also be included if the intensity of the signals is not sufficient to produce the desired keying. A wave form of the voltage variations appearing at condenser 84 is shown at 75, the blanking or keying signals extending in a positive direction. When these signals are applied to the control electrode of tube 70 by means of condenser 84, the tube 70 is rendered conductive only during the line blanking signal intervals. During these intervals the output from the amplifier 66 is effective to modulate the electron stream in the tube 70. This produces a voltage variation at the anode of the tube and these voltage variations are applied to a final amplifier and/or frequency multiplier 86 by way of condenser 88. The output from the amplifier 86 is then supplied to a sound transmitting antenna 90.

When blanking or keying signals, such as are shown at the curve 75, are applied to the control electrode of tube 70, the tube is rendered conductive or operative during intervals of picture line blanking. Only at this time are the frequency modulated oscillations permitted to

pass through the tube 70 and be applied to the amplifier and/or frequency multiplier 86. During other intervals, the tube 70 is blocked so that no radio frequency energy is available at the input of the amplifier or frequency multiplier 86. The carrier is therefore completely eliminated between intervals of horizontal blanking and synchronization, during which time picture signals are transmitted.

10 Through the use of the above described system it is, therefore, possible to transmit sound by frequency modulating an oscillator, the radio frequency energy being transmitted only during the intervals when the horizontal blanking and synchronizing impulse occurs. At all other times the sound carrier is completely eliminated so that the picture signal carrier may then be modulated by picture signals over a band such as will produce side band frequencies of the order of 4.75 megacycles from the picture signal carrier frequency and the receiver may be made responsive to this band of frequencies without resulting in interference from the sound channel.

25 Inasmuch as the synchronizing signals do not produce side bands that are as extensive as the side bands produced by the picture signals, there is no possibility of interference between the synchronizing signals and the sound signals during their simultaneous transmission. In view 30 of the fact that the sides of the synchronizing signals, when transmitted in accordance with present standards, are quite steep, frequencies of the order of 3.0 to 3.5 megacycles may be produced, however, these frequencies do not completely fill the space between the picture signal and synchronizing signal carrier and the sound signal carrier.

35 The present system has certain limitations which are inherent in the system. Since the 40 sound signals are transmitted at intervals which occur at horizontal synchronizing frequency naturally the highest audio frequency that can be transmitted will correspond to approximately one-half the horizontal synchronizing signal frequency. In present television systems transmission is carried out at 525 lines per frame. The frame repetition rate being 30. The horizontal synchronizing and blanking frequency has therefore 45 15,750 cycles per second. In sequential color television, however, the transmission may be at the rate of 405 lines per frame, and a frame frequency of 60 cycles per second (120 fields interlaced two to one). Under these conditions the horizontal blanking and synchronizing frequency would be 24,300 cycles per second.

50 It is desirable also that the harmonics which are transmitted in the sound channel be limited so that they will not interfere with signals in the next adjacent television band. To reduce these harmonics it is preferable that the wave form of the control impulses 75 that are applied to the control electrode of tube 70 be somewhat rounded. Any slight attenuation of the high frequencies, however, will be entirely sufficient since the sound carrier is positioned 250,000 cycles below the upper limit of the particular television band. A limitation of all harmonics above the tenth harmonic of the controlling frequency of 15,750 cycles per second (the sixth harmonic in the above example of color television) would therefore be completely adequate to eliminate any possibility of interference with the next adjacent television channel. For eliminating all harmonics above the tenth harmonic of the line repetition rate a small condenser 92 may

be employed. In many cases the distributed capacity of the conductor connecting the horizontal blanking and synchronizing signal channel with the control tube 70 will be sufficient to eliminate any such interference.

Although the system is described as being applied to a frequency modulated sound carrier, it is to be understood that an amplitude modulated sound carrier may likewise be controlled since in so far as the present invention is concerned it is immaterial whether frequency or amplitude modulation is employed for the transmission of sound. If amplitude modulation is employed then naturally amplitude modulators will be used in place of a frequency modulated oscillator, however, a control tube similar to that shown in the figure may as conveniently be used to permit or prevent the transmission of amplitude modulated radio frequency energy to the final radio frequency amplifier.

Although the present invention is described as applicable to a transmitting tube of the "Iconoscope" type, naturally the present invention may also be applied to any type television transmitting tube since it is immaterial where the particular picture signals are derived. Furthermore, the picture signals and synchronizing signals may be used to amplitude or frequency modulate the carrier used for such transmission.

The present invention has the particular advantage that it may be exercised or put into practice without causing any undesired effects in so far as television receivers which are at present in use are concerned since no change need be made in such receivers. The same picture and sound carriers are used and the carriers are displaced by the same amount.

In television receivers that are designed to receive sound transmitted as a frequency modulation of a carrier and wherein a limiter is used, it may be desirable under some circumstances to provide a limiter which will not only remove noise from the top of the frequency modulated carrier envelope but also provide a limiter or circuit arrangement whereby low levels of amplitude modulation could also be removed. Since the frequency modulated carrier is available only at spaced intervals, noise which appears as an amplitude modulation might, in some instances, be effective to produce noise at the sound receiver unless some means were provided to remove the noise between sound transmission intervals. Noise, which is superimposed upon the frequency modulated sound carrier (during intervals of transmission) is naturally removed by the limiter in its usual method of operation.

Various alterations and modifications of the present invention may become apparent to those skilled in the art and it is desirable that any and all such modifications and alterations be considered within the purview of the present invention except as limited by the hereinafter appended claims.

I claim:

1. A television transmitting system comprising a source of picture signals, a source of synchronizing signals, means for combining the picture signals and synchronizing signals, a source of radio frequency carrier energy, means for modulating the source of radio frequency carrier by the combined picture and synchronizing signals, a source of audio signals related to the picture signals, a second source of radio frequency carrier energy of a frequency differing from the frequency of the first radio frequency carrier by

5 a predetermined amount, means for modulating the second radio frequency carrier by the audio frequency, and means to interrupt the transmission of the audio frequency modulated radio frequency carrier during the intervals when the first radio frequency carrier is modulated by picture signals.

2. A television transmitting system including a source of picture signals and a source of synchronizing signals, means for combining the picture and synchronizing signals to produce a composite series of signals, a first source of radio frequency energy, means for modulating the first source of radio frequency energy by the combined picture and synchronizing signals, a source of audio frequency, a second source of radio frequency energy, means to modulate said second source of radio frequency energy by said audio frequencies, means to interrupt said second radio frequency energy during the transmission of picture signals and means to transmit said second radio frequency energy during the transmission of synchronizing signals only.

3. A television transmitting system including a source of picture signals and a source of synchronizing signals, means for combining the picture and synchronizing signals to produce a composite series of signals, a first source of radio frequency energy, means for modulating the first source of radio frequency energy by the combined picture and synchronizing signals, a source of audio frequency, a second source of radio frequency energy, means to modulate said second source of radio frequency energy by said audio frequencies, and means to interrupt the modulation of said second radio frequency energy during the modulation of said first radio frequency energy by picture signals and to modulate said second radio frequency energy during synchronizing signal modulation of said first radio frequency carrier.

4. A television transmitting system wherein picture and synchronizing signals are transmitted as a modulation of one carrier frequency and wherein the related sound signals are transmitted as a modulation of a second radio frequency carrier, comprising a combined series of picture and synchronizing signals, a first radio frequency carrier, means to modulate said first radio frequency carrier by said combined picture and synchronizing signals, a second radio frequency carrier, a source of related sound signals, means to modulate said second radio frequency carrier by the sound signals during modulation of said first radio frequency carrier by synchronizing signals only, and means to prevent the modulation of said second radio frequency carrier during periods of modulation of said first radio frequency carrier by said picture signals.

5. A television transmitting system wherein picture and synchronizing signals are transmitted as a modulation of one carrier frequency and wherein the related sound signals are transmitted as a modulation of a second radio frequency carrier, comprising a combined series of picture and synchronizing signals, a first radio frequency carrier, means to modulate said first radio frequency carrier by said combined picture and synchronizing signals, a second radio frequency carrier, a source of related sound signals, means to modulate said second radio frequency carrier by said related sound signals, means to transmit said modulated second radio frequency carrier only during transmission of

said first radio frequency carrier when modulated by synchronizing signals and means to prevent the transmission of said second radio frequency carrier during transmission of said first radio frequency carrier when modulated by picture signals.

6. A television transmitting system including a source of picture signals, a source of synchronizing signals, a source of radio frequency energy, means to modulate said source of radio frequency energy alternately by said picture and synchronizing signals, a source of related sound signals, a second source of radio frequency energy, means to modulate said second source of radio frequency energy by said sound signals, and means to transmit said modulated second radio frequency energy only during intervals of modulation of said first radio frequency energy by said synchronizing signals.

7. A television transmitting system including a source of picture signals, a source of synchronizing signals, means to combine the picture and synchronizing signals to produce a composite series of signals, a source of radio frequency carrier energy, means to modulate said source of radio frequency carrier energy alternately by said combined picture and synchronizing signals, a source of related sound signals, a second source of radio frequency carrier energy, means to modulate said second source of radio frequency carrier energy by said sound signals, and means to cause transmission of said modulated second radio frequency carrier only during intervals of modulation of said first radio frequency carrier by said synchronizing signals.

8. A television transmitting system including a source of picture signals, a source of synchronizing signals, means to combine the picture and synchronizing signals, a first source of radio frequency energy, means to alternately modulate said first source of radio frequency energy by said combined picture and synchronizing signals, a source of related sound signals, a second source

of radio frequency energy, means to modulate said second source of radio frequency energy by said sound signals, an electron discharge tube including a cathode, a control electrode and an output electrode, means to maintain the output electrode positive with respect to its associated cathode, means to apply said sound modulated radio frequency energy to said control electrode, means to bias the potential of said control electrode relative to the cathode by an amount sufficient to prevent electronic conduction through said tube, and means to apply control impulses of synchronizing signal frequency to said control electrode to render said tube conductive at predetermined intervals, whereby sound signal modulated radio frequency energy is available from the output electrode of said tube only during such intervals.

9. A television transmitting system including a source of picture signals, a source of synchronizing signals, means to combine the picture and synchronizing signals, a first source of radio frequency energy, means to alternately modulate said first source of radio frequency energy by said combined picture and synchronizing signals, a source of related sound signals, a second source of radio frequency energy, means to modulate said second source of radio frequency energy by said sound signals, an electron discharge tube including a cathode, a control electrode and an output electrode, means including a load circuit to maintain the output electrode positive with respect to its associated cathode, means to apply said sound modulated radio frequency energy to said control electrode, means to normally prevent electronic conduction through said tube, and means to apply control impulses of synchronizing signal frequency to said control electrode to render said tube conductive at predetermined intervals, whereby sound signal modulated radio frequency energy is available from the output electrode of said tube only during such intervals.

ROBERT E. SHELBY.
